UNITED STATES PATENT OFFICE.

FREDERICK W. GRELL, OF NEW YORK, N. Y., ASSIGNOR TO AMERICAN HARD RUBBER COMPANY, A CORPORATION OF NEW YORK.

DESIGN FOR A COMB.

No. 39,170.

Specification for Design.

Patented March 3, 1908.

Application filed December 20, 1907. Serial No. 407,434. Term of patent 14 years.

To all whom it may concern:

Be it known that I, FREDERICK W. GRELL, a citizen of the United States, residing at New York, in the county of New York and State of New York, have invented a new, original, and ornamental Design for Combs, of which the following is a specification, reference being had to the accompanying drawing, forming part thereof.

In said drawing, Figure 1 shows a side elevation of a comb comprising said design, and Fig. 2 a top view of such comb.

What I claim is:—

The ornamental design for a comb, as shown.

FREDERICK W. GRELL.
